CLAIM

The ornamental design for a user interface panel, as shown and described.

DESCRIPTION

FIG. 1 is a front and bottom perspective view of a user interface panel of the new design;

FIG. 2 is a front view of the design of FIG. 1;

FIG. 3 is front, left, and lower perspective view of a front portion of the user interface panel of FIG. 1

FIG. 4 is a front plan view of the front portion of the user interface panel of FIG. 1;

FIG. 5 is a front elevation view of the front portion of the user interface panel of FIG. 1;

FIG. 6 is a top view of the front portion of the user interface panel of FIG. 1;

FIG. 7 is a bottom view of the front portion of the user interface panel of FIG. 1;

FIG. 8 is a right side view of the user interface panel of FIG. 1;

FIG. 9 is a left side view of the user interface panel of FIG. 1;

FIG. 10 is a top view of the user interface panel of FIG. 1;

FIG. 11 is a bottom view of the user interface panel of FIG. 1;

FIG. 12 is a left side view of the front portion of the user interface panel of FIG. 1; and,

FIG. 13 is a right side view of the front portion of the user interface panel of FIG. 1.

The broken lines in the drawings depict portions of the user interface panel that form no part of the claimed design.

1 Claim, 13 Drawing Sheets
